DESIGN FOR A DRESS ENSEMBLE

Elizabeth M. Ciccone, New York, N. Y.

Application June 23, 1938, Serial No. 77,997

Term of patent 3½ years

To all whom it may concern:

Be it known that I, Elizabeth M. Ciccone, a citizen of the United States of America, residing in the city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a front view of the dress member of the ensemble.

Fig. 3 is a rear view of Fig. 1.

Fig. 4 is a rear view of Fig. 2.

The characteristic feature of my design resides in the combination on the ensemble disclosed of the specific applique on the front portion of the jacket of the ensemble as shown.

I claim:

The ornamental design for a dress ensemble, substantially as shown and described.

ELIZABETH M. CICONE.
